UNITED STATES PATENT OFFICE.

AUGUST OSENBRÜCK, OF HEMELINGEN, PRUSSIA, GERMANY.

REFRIGERATING-MACHINE.

SPECIFICATION forming part of Letters Patent No. 375,188, dated December 20, 1887.

Application filed July 10, 1885. Serial No. 171,926. (No model.)

To all whom it may concern:

Be it known that I, AUGUST OSENBRÜCK, a subject of the King of Prussia, residing at Hemelingen, in the Kingdom of Prussia, German Empire, have invented new and useful Improvements in Refrigerating-Machines, of which the following is a specification.

This invention relates to an apparatus intended for collecting and saving the refrigerating fluids or gases used in an ice-making or other refrigerating machine which are found to escape from certain parts of the apparatus, even when constructed with the utmost care and skill. It is particularly adapted for use 15 with ice-machines of the condensing type, wherein the ammoniacal vapor is converted into liquid form by pressure in a condensing cylinder or chamber. It is found almost impossible in such machines to so construct the 20 stuffing-boxes surrounding the sliding rods entering such chamber as to prevent leakage, and it is in connection with such an apparatus and to collect such waste or leakage of the refrigerating gas or fluid that I have illustrated my invention and will hereinafter describe it.

Figure 1 is a diagrammatic illustration of my invention, parts thereof being shown in section. Fig. 2 is an enlarged sectional view of the change-valve. Fig. 3 is an enlarged section 30 view of the stuffing-boxes of the compressor and a charging-cylinder connected therewith.

As my invention may be used in connection with any style of refrigerating apparatus, I 35 have not illustrated any such device, simply showing in the drawings one head, A', of a compressing-cylinder, forming part of the main refrigerating apparatus, to the end of which is secured the stuffing-boxes A, for the 40 sliding rods entering therein—as the piston-rod Y and valve-rod X, Fig. 3, these latter parts being illustrated in Fig. 1 only sufficiently for an understanding of this invention, while in Fig. 3 they are shown in detail. 45 Communicating with these stuffing-boxes is a chamber, N, filled with some absorbing-liquid, wherein is collected any of the refrigerating liquids or gases that may escape from the condenser along the rods X or Y past the stuffing-boxes. This charging-chamber N is in com-

munication with a still, E, by two lines of pipe, that conducting the charged liquid to the still and leading from the top of the charging-chamber N being designated by the numeral 2, and that returning the liquid from 55 the still to the charging-chamber after it has been freed from the charge of gas being numbered 3.

To maintain a circulation of the absorbing-liquid through pipes 2 and 3, the still, and the 60 charging-chamber, a pump, as B, may be employed, it being shown in the drawings as situated in pipe 2 between the charging-chamber and the still, although I do not wish to be limited to the position there shown. 65

D is a chamber forming part of the return-pipe 3, within which is arranged a worm, b, formed in pipe 2. The chamber D receives the hot liquid shortly after it leaves the still, when it imparts some of its heat to the liquid in the worm on its way to the still, thereby raising its temperature in a corresponding degree to which its own temperature is reduced.

1 is an expansion coil or other cooling device situated in the absorbing-chamber N, and 75 serving to reduce the temperature of the absorbing liquid contained therein, in order to increase its power of taking up the waste gases and liquids.

Any suitable absorbing-liquid may be employed in chamber N, although I have found a hydrocarbon liquid known as "oleo-naphtha," obtained from Nizhnee-Novgorod, Russia, to be well adapted therefor.

The charged liquid being impelled by a 85 pump, B, or other motive power, passes through pipe 2 until it reaches the worm b, where its temperature is raised by the hot return liquid preparatory to its being discharged into the upper portion of the still. 90 It is herein subjected to heat, which results in freeing it from the ammoniacal vapors with which it is charged, which, being set free, may be carried off by pipe 4 to the suction-pipe of the compressor or other desired point in the 95 refrigerating apparatus. As the liquid becomes freed from its charge, it becomes heavier and gradually sinks to the bottom of the still, where it passes out through pipe 3 free from its charge. From the still it first passes into 100

the chamber D, where it exchanges a portion of its high temperature for the lower temperature of the charged liquid flowing through worm b, as has been described; thence it passes 5 to any desired form of cooler, as that indicated at F, and back to the charging-chamber, entering the lower portion thereof, where its temperature is sufficiently lowered by coil 1 to prepare it for again absorbing the waste- 10 refrigerating liquid or gas.

I will now describe the construction of stuffing-boxes surrounding rods X Y, which I prefer to employ, reference being had to Fig. 3.

L M indicate the necks of the stuffing-boxes 15 of the piston-rod and slide-rod, respectively, situated between the compressor and the chamber N, they containing the usual packing material which surrounds the rods, and is held under suitable compression therein by the 20 glands a b', surrounding the rods Y X, and which are adjustable thereon by means of the screws g c and suitable nuts thereon, as will be understood without further explanation. The interior of glands a b' are chambered, as 25 at e f, the walls of the chambers being provided with radial apertures, these chambers and apertures serving to permit any of the volatile refrigerating material which may possibly escape past the stuffing-boxes in necks L M to 30 pass into the chamber N, where it will be absorbed by the liquid contained therein and circulating through the same. This absorbing-fluid is prevented from escape along glands a b', or the sliding rods Y X, by means of glands 35 O P and d d, adjustable independently of each other, and of the glands a b' by means of the nuts bearing against the same and moving upon screw-rods g c, as will be understood by reference to the drawings.

40 C indicates a change valve, situated in the pipes 2 and 3, between the still and charging-chamber, when the latter is open to the atmosphere, this valve serving to prevent the pressure in the still upon the absorbing-liquid 45 therein from blowing the same out into the atmosphere and preventing the working of the apparatus. This valve is represented in detail in Fig. 2, to which reference is now made. It consists of valves H I, which are retained 50 upon their seats by springs b², surrounding the stems C' of the valves. The valve I is situated in passage 2 and serves to close it, when forced upon its seat, against passage of liquid from the charging-chamber to the still. The 55 valve H is situated in passage 3, and closes it against the passage from the still to the charging-chamber. The upper ends of the valve-stems C' C' bear, respectively, against the opposite ends of a rock-lever, X, the arrangement thereof and of the springs b² being such 60 that the valves will be opened and closed simultaneously. The action of the pump forcing the liquid through pipe 2 against the valve I, serves to raise the latter, opening the passage closed thereby, and hence, through the valve-stems and rock-lever, also opening the

passage in pipe 3, closed by the valve H. Communication will thus be established between the charging-chamber and the still, which will be maintained so long as the pump is in operation. Should this operation, however, from any cause cease, the pressure of springs b² and of the liquid under pressure from the still on the face of valve H will result in closing both 70 passages 2 and 3, and thus prevent the liquid 75 from being forced out by the pressure in the still.

The tension of the springs b² is adjustable by means of movable collars b³.

It will be understood that when a receiver, 80 N, for the absorbing-fluid, which is hermetically sealed, is employed, a change-valve such as just described need not be used.

I do not wish to be limited to the exact arrangement of parts shown, or to all the details 85 of construction illustrated and described, as they may be modified to a certain extent without departing from the spirit of my invention.

What I claim is—

1. In combination with a compressor-cylinder or equivalent part of a refrigerating apparatus having a moving rod extending therefrom, a stuffing-box for said rod, the gland whereof is chambered, as at e, and provided with apertures, a chamber containing an absorbing-liquid communicating through said apertures with the chambered gland, whereby any gas or liquid which may pass the stuffing-box will be absorbed by the liquid in the chamber, and a still and communicating-pipes between the still and chamber, substantially as described. 90

2. In combination with a compressor-cylinder or equivalent part of a refrigerating apparatus and a sliding rod, Y, extending therefrom, a stuffing-box consisting of a neck, L, and a gland, a, the latter being chambered, as at e, and provided with apertures, a chamber, N, containing an absorbing-fluid communicating with said chamber e through the apertures, a gland, O, surrounding gland a on the side of the chamber N, opposite the neck L, another gland, b', surrounding the shaft beyond the gland O, and forming with the end of gland a a stuffing-box, a screw-threaded 105 rod, g, and nuts thereon bearing, respectively, against glands O a d, whereby they are separately and independently adjustable, substantially as set forth. 110

3. The combination of a still, an absorbing-chamber, communicating circulating-pipes between the still and absorbing-chamber, a pump for maintaining a circulation through the same, and a valve situated in the return-pipe from the still to the absorbing-chamber, normally held closed and adapted to be forced 115 from its seat when the pump is in operation, substantially as set forth. 120

4. The combination of a still, an absorbing-chamber communicating therewith, communicating-pipes 2 3 between the same, a pump for 125 maintaining circulation through the pipes, 130

still, and chamber, valves I H, adapted to close said pipes, respectively, a spring for closing said valves when the pump is not in operation, and a connection between said 5 valves, as rock-bar X, whereby they are simultaneously opened or closed, substantially asset forth.

In testimony whereof I have signed my name to this specification in the presence of two subscribing witnesses.

AUGUST OSENBRÜCK.
